DESIGN FOR A MOVING PICTURE FILM REEL

Jacob M. Goldberg, Denver, Colo.

Application May 16, 1944, Serial No. 113,602

Term of patent 14 years

(Cl. D61—1)

To all whom it may concern:

Be it known that I, Jacob M. Goldberg, a citizen of the United States, residing in the city and county of Denver and State of Colorado, have invented a new, original, and ornamental Design for a Moving Picture Film Reel, of which the following is a specification, reference being had to the accompanying drawing, forming part thereof.

In the drawing:

Figure 1 is a plan view of a moving picture film reel showing my new design;

Figure 2 is a side elevational view thereof; and

Figure 3 is a section taken on line 3—3, Figure 1.

I claim:

The ornamental design for a moving picture film reel, as shown.

JACOB M. GOLDBERG.
